United States Patent Office.

A. B. BEAN, OF NEW HAVEN, CONNECTICUT.

Letters Patent No. 91,072, dated June 8, 1869.

IMPROVED RATCHET-FEED.

The Schedule referred to in these Letters Patent and making part of the same

To all whom it may concern:

Be it known that I, A. B. BEAN, of New Haven, in the county of New Haven, and State of Connecticut, have invented a new Improvement in Ratchet-Feed; and I do hereby declare the following, when taken in connection with the accompanying drawings, and the letters of reference marked thereon, to be a full, clear, and exact description of the same, and which said drawings constitute part of this specification, and represent in—

Figure 1, a front view, and in

Figures 2, 3, and 4, sectional views illustrating the three different positions.

This invention relates to an improvement in the ratchet-feed, for which Letters Patent were granted to me, bearing date December 1, 1868, and is especially adapted to iron-planers, but applicable to various kinds of machines; and

The invention consists in a double pawl having arranged within it a cam fixed to the bearing upon which the pawl turns, and a spring-head within the pawl, which will pass over the cam so as to hold the pawl centrally free from the ratchet-wheel, or turned to either side for the purpose of feeding, as the case may be.

To enable others skilled in the art to fully understand my invention, I will proceed to describe the same, as illustrated in the accompanying drawings.

A is the ratchet-wheel fixed to the shaft B, the said shaft being in connection with whatever it is desirable to feed.

C is a lever to which power is applied for operating

the feed, which imparts to the lever a vibratory movement on the shaft B.

On the said lever is fixed a stud, D, over which a double-ended pawl, E and F, is placed, turning freely on the stud D to the right or left, as from the position in fig. 3 to that in fig. 4, and *vice versa*, this change reversing the action of the feed.

Within the pawls a recess, H, is formed, so as to receive therein a cam, I, which is rigidly fixed to the stud D by a set-screw or otherwise, and in the handle L of the pawls a head, N, is arranged, so as to be forced down on the cam by a suitable spring, the upper end of the cam being constructed so as to receive the end of the head, as seen in fig. 2, and hold the pawls in a central position so that the vibration of the lever C has no effect upon the wheel A.

If desired to turn the wheel A to the left, touch the handle L and press it over to the position seen in fig. 3. The head N being easily forced from off the cam I, and falling down to the left of the cam, holds the pawl in that position.

If desired to turn the wheel A in the opposite direction, press the handle over, as seen in fig. 4.

Having fully described my invention,

What I claim as new and useful, and desire to secure by Letters Patent, is—

The arrangement of the fixed cam I within the double pawl E and F, and combined with the head N, so as to operate substantially in the manner set forth.
